UNITED STATES PATENT OFFICE.

LANE JOHNSON, OF INGRAM, PENNSYLVANIA, ASSIGNOR TO UNITED ENGINEERING AND FOUNDRY COMPANY, OF PITTSBURGH, PENNSYLVANIA, A CORPORATION OF PENNSYLVANIA.

REEL.

Application filed December 2, 1922. Serial No. 604,486.

To all whom it may concern:

Be it known that I, LANE JOHNSON, a citizen of the United States, residing at Ingram, county of Allegheny, and State of Pennsylvania, have invented a new and useful Improvement in Reels, of which the following is a full, clear, and exact description.

The present invention relates broadly to 10 reels and more particularly to reels adapted for use with rolling mills producing strips, the word strips being used in its generic sense as covering shapes having a substantially rectangular section, or section of such 15 nature that the material is adapted to be wound into a helix or series of superimposed coils.

It is customary at the present time for 20 strip mills to deliver strips at a speed of from six hundred to one thousand feet a minute. As the strip is at a high temperature as it leaves the rolls, it is necessary to provide some means for the proper disposition of the strip to prevent injury to the 25 workmen. In the usual practice, the strip is permitted to loop at will on a comparatively flat surface. This operation is not altogether satisfactory and has heretofore resulted in serious injuries to workmen who 30 became entangled in these coils.

By the present invention, there is provided a reel adapted to co-operate with a hot strip mill and receive the strip as it is delivered by the last stand of rolls and coil 35 the same into a definite shape. In this manner, it is possible to obviate all of the objections to the present practice of handling the rolled strip.

In the accompanying drawings there is 40 shown, for purposes of illustration only, a preferred embodiment of the present invention, it being understood that the drawings do not define the limits of the invention and that changes may be made in the construction 45 and operation disclosed therein without departing from the spirit or scope of my broader claims.

In the drawings,

Figure 1 is a side elevation of a reel embodying the present invention;

Figure 2 is an end elevation of the construction shown in Figure 1;

Figure 3 is a top plan view of one of the supporting means for one of the guiding devices, and

Figures 4, 5 and 6 are perspective views illustrating the supporting means for other of the guiding devices.

In accordance with the present invention, a hot strip mill reel may be formed of a 50 suitable supporting frame preferably comprising side standards 2 which may be of substantially similar construction. These standards are adapted to receive therebetween and operatively support a series of 55 guiding devices adapted to co-operate with the strip as it is fed to the reel. These guiding devices may conveniently comprise a series of rolls 3 and intermediate deflectors 4. These rolls and deflectors form a sub- 60 stantially enclosed circular coiling space.

Adapted to deliver a strip to the guiding devices are pinch rolls 5 carried by the standards 2 and spaced to receive a strip S therebetween. One of these rolls may be 75 positively driven by providing a pulley 6, or may be otherwise driven as explained hereinafter. The pinch rolls pass the strip through a guide 7 to the guiding devices 3 and 4. As these guiding devices form a 80 substantially enclosed coiling space, it will be apparent that the entering end of the strip is immediately bent and caused to pass successively to the different guiding devices. After the first complete coil is formed, it 85 will be obvious, it will be necessary to permit outward movement of the guiding devices in order to compensate for the increased diameter of each succeeding layer.

This compensation may conveniently be 90 obtained by so mounting certain of the guiding devices that they may move outwardly under the action of the strip being coiled. In the specific embodiment of the invention illustrated, this construction comprises angularly arranged arms 8, illustrated in detail in Figure 5, for one of the rolls 3 and a slightly modified construction 9 for certain other of the guiding rolls. The arms 8 and 95 9 may conveniently be formed as castings 100 having their inner ends connected to form the deflectors 4 and having their outer ends connected by hubs 10 of a length substantially extending from standard to standard

to thereby prevent end play of the guiding devices, the standards being held in proper position in any desired manner as by bolts 11 any number of which may be provided.

8 At the outer end of the guide 7 the guide roll 3^a is carried between the standards on pivot 12^a. This pivot also supports arms 12 shown in detail in Figure 3, which arms carry the upper pinch roll 5. The first deflector 4 may be carried by arms 13, as illustrated in detail in Figure 4. While all of the different arms provided might be of similar construction, the modified construction herein disclosed has been found desirable from a constructional and assembly standpoint, the arrangement permitting a compact organization. Each pair of arms 8, 9, 12 and 13, has extending outwardly therefrom a crank arm 14 which crank arms 20 co-operate with tension springs 15 for continuously exerting a pull on the crank arms effective for urging the guiding devices, with the exception of the roll 3^a, inwardly. These springs at the same time permit all of the guiding devices to move outwardly as the diameter of the coil increases.

The inward movement of the guiding devices may be checked in any desired manner. For this purpose there may be provided 30 links 16 for certain of the guiding devices, which links are secured at their outer ends to the bolts which hold the arms in position in the supporting frame and at their inner ends are provided with hooks 17 adapted to engage the axes of the rolls 3. The arms 18 may conveniently be controlled by a stop 19 formed on one of the side standards and adapted to co-operate with an abutment 19 on the crank arm 14. Each of the springs 40 15 may have its tension adjustably controlled in any desired manner, as will be apparent.

In order to decrease the friction exerted on the strip being coiled, the rolls 3, together with the rolls 3^a and 3^b which are directly carried between the side standards, are all adapted to be positively driven. This action may be accomplished by extending the axes of all of these rolls beyond one 45 of the side standards 2 and connecting thereto one end of a drive shaft 20 having a universal joint 21 at each end thereof. These universal joints may be of any well known construction and are preferably so secured 50 to the shafts 20 as to permit the distance between the universal joints to increase or decrease without destroying the driving relationship. This arrangement will take care 55 of the outward movement of the guiding devices and enable the rolls to be continuously driven. At their outer ends all of the shafts 20 may be supported in a supplemental standard 22 having a series of bearings 23 for the shafts. Each of the shafts 60 has secured thereto a gear 24 all of which

gears are in turn driven by large gear 25 mounted on a shaft 26 and adapted to be driven by a pulley 27. I have also illustrated the shaft for the pulley 6 as being extended and connected to a shaft 20 whereby the pinch rolls 5 may be driven simultaneously with all of the guiding rolls.

The present invention enables a hot strip to be coiled into compact shape as it is delivered from the last roll stand. As the 75 guiding devices are all movable about axes which are parallel, the strip is caused to form a series of superimposed convolutions so that the entire body of rolled material is maintained in position between the standards 2. In this manner, the possibility of injury to the workmen is negated and the space heretofore required for the looping of the hot metal may be utilized for other purposes. These constitute advantageous features of the invention.

This invention also overcomes the objections inherent in the use of a hot bed, such as heretofore sometimes used for the strips. The length of the hot bed limits the weight 90 of the billet being rolled, as the length of the strip produced therefrom must not exceed the length of the hot bed. The present reel takes care of varying lengths of material in much less space than has heretofore been possible.

I claim:

1. In a reel, a supporting frame, and a plurality of strip guiding devices forming a substantially enclosed circular unobstructed coiling space and adapted to co-operate with a strip fed to said reel and form the same into a series of superimposed convolutions, said guiding devices being movable outwardly under the action of the material being coiled, substantially as described.

2. In a reel, a supporting frame, and a plurality of outwardly movable strip guiding devices adapted to co-operate with the strip fed to said reel and form the same into a series of superimposed convolutions, said devices comprising deflectors carrying intermediate anti-friction rolls independently of any interior mandrel, substantially as described.

3. In a reel, a supporting frame, and a plurality of outwardly movable strip guiding devices adapted to co-operate with a strip fed to said reel and form the same into a series of superimposed convolutions, said devices comprising a series of pivotally mounted arms carrying positively driven anti-friction rolls and intermediate deflectors filling substantially all the space between the rolls when the reel is in strip receiving position, substantially as described.

4. In a reel, a supporting frame, and a plurality of outwardly movable strip guiding devices forming a substantially enclosed circular coiling space and adapted to co-op-

erate with a strip fed to said reel and form the same into a series of superimposed convolutions, said guiding devices comprising spaced deflectors and a series of positively 5 driven rolls carried thereby, substantially as described.

5. In a reel, side frames, at least one of said side frames being cut away to permit removal of a coil therethrough, means carried by said frames to coil material fed thereto, said means comprising a fixed roll and deflector and a plurality of pivotally mounted rolls and deflectors all movable about parallel axes, and means for driving 10 said rolls, substantially as described.

6. In a reel, a supporting frame, and a plurality of outwardly movable strip guiding devices forming a substantially enclosed unobstructed circular coiling space and 20 adapted to co-operate with a strip fed to said reel and form the same into a series of superimposed convolutions, said guiding devices comprising a series of rolls rotatable about parallel axes and a series of deflectors 25 movable about axes parallel to said first mentioned axes, substantially as described.

7. In a reel, side frames, at least one of said side frames being cut away to permit removal of a coil therethrough, means carried by said frame to coil material fed thereto, said means comprising a fixed roll and deflector and a plurality of pivotally mounted rolls and deflectors all movable about parallel axes, means for driving said 30 rolls, means urging said pivotally mounted rolls inwardly, and means limiting such inward movement, substantially as described.

8. In a reel, a supporting frame, and a plurality of outwardly movable strip guiding devices forming a substantially enclosed unobstructed circular coiling space, said devices being adapted to cooperate with a strip fed to said reel to form the same into a series of superimposed convolutions and 40 comprising a series of positively driven 45

rolls and intermediate deflectors carrying the same, substantially as described.

9. In a reel, a supporting frame, a plurality of outwardly movable strip guiding devices forming a substantially enclosed unobstructed circular coiling space, said devices being carried by said frame and adapted to cooperate with a strip of material fed to said reel to form the same into a series of superimposed convolutions, a second 50 frame spaced from said supporting frame, and driving means extending from said second frame to said supporting frame for positively operating said guiding devices, 55 substantially as described.

10. In a reel, a supporting frame, a plurality of outwardly movable strip guiding devices comprising a series of uniformly spaced antifriction rolls and intermediate deflectors, a second frame, a plurality of flexible shafts extending from said second frame to said antifriction rolls for positively driving the same, and means carried by said second frame for rotating said shafts, substantially as described. 60

11. In the method of rolling metal strips, the step consisting in passing the strips directly from the last roll stand to a coiling device and continuously forming said strips into a series of superimposed convolutions 75 having the interior of the inner convolution unobstructed, said coiling occurring simultaneously with the rolling, substantially as described.

12. In the method of rolling metal strips, 80 the step consisting in passing the strips from the last roll stand to a coiling device and continuously forming said strips as delivered from the last roll stand into a series of superimposed convolutions having the interior of the inner convolution unobstructed, 85 substantially as described.

In testimony whereof I have hereunto set my hand.

LANE JOHNSON.
